UNITED STATES PATENT OFFICE.

FRANCIS WILLIAM STOKES, OF NOTTINGHAM, ENGLAND.

CASTING-MACHINE.

1,309,823.

Specification of Letters Patent. Patented July 15, 1919.

Original application filed July 9, 1918, Serial No. 244,099. Divided and this application filed February 14, 1919. Serial No. 277,080.

To all whom it may concern:

Be it known that I, FRANCIS WILLIAM STOKES, a subject of the King of Great Britain, residing at 20 Alexandra avenue, Mansfield, Nottingham, England, have invented new and useful Improvements in Casting-Machines, of which the following is a specification.

This invention relates to casting machines of the kind in which a rotating mold is made use of, into which the metal or other material to be cast is introduced through a centrally arranged pourer which is carried by a supporting stem or spindle and is furnished with a storage receptacle or reservoir mounted eccentrically with respect to the pourer. My invention comprises certain improvements in pouring devices of this type for the purpose of improving their efficiency and rendering them more adaptable for use in specific cases. This application is a division of my application Serial No. 244,099, filed July 9, 1918, which resulted in Letters Patent No. 1,302,448.

25 A pouring device according to the invention is mounted upon a swivel support upon which the stem or spindle of the pourer is rotatably carried and which is itself supported upon a trolley arranged to run upon rails on the bed-plate of the machine. The pourer may be constructed for the purpose of introducing more than one class of metal into the mold, in which case it may be subdivided into compartments each of which 30 is provided with its own pouring opening displaced relatively to the other, the arrangement being such that when the pourer is tilted the metal is discharged in succession from the compartments.

40 In the accompanying drawings—

Figure 1 is a side elevation of one form of centrifugal casting machine constructed according to the invention.

Fig. 2 is an end view, thereof.

45 Fig. 3 is a section on the line 3—3, Fig. 1. Figs. 4 and 5 are a side view and a plan view respectively illustrating a modified form of pourer, and

50 Figs. 6 and 7 are transverse sections respectively on the lines 6—6, and 7—7 of Fig. 4.

55 Referring first to the construction illustrated in Figs. 1 to 3, *a* indicates the bed-plate of the machine and *b* is the mold which is made in two parts and is carried

by the face-plate *c*, which is keyed upon the spindle *d* mounted in bearings *d*¹ on the bed-plate *a* of the machine and designed to be rotated from any suitable source of power.

60 *e* is the door of the mold and *f* are centrifugally controlled locking levers which are pivoted at *f*¹ to the outer end of the mold, the said levers being formed with hooks *f*² at one end and carrying weights *f*³ at the other end.

65 The pouring device comprises the pourer *l* which is furnished with a pouring lip *l*¹ and with an eccentric storage receptacle or vessel *m*, these two parts being carried by the spindle *n* mounted in bearings *n*¹, *n*¹ upon the swivel or capstan head *n*² which can be turned on the trolley *o* designed to run on rails *o*¹ on the bed-plate *a*. This swivel-head enables the pourer *l* to be turned away from the mold to allow of access thereto to remove the casting therein after the casting operation. Stops *n*³ are provided for limiting the turning movement of the swivel-head *n*² in either direction. The spindle *n* is furnished with a hand-wheel *p* by means of which the said spindle and consequently the pourer can be turned when the latter is inserted within the mold *b*.

70 As will be understood, by tilting the said pourer *l*, which is mounted so that it enters the mold in an axial direction, the molten metal which is contained in the reservoir *m*, is caused to run from the latter and escapes over the lip *l*¹ into the mold, where it is subject to the action of centrifugal force and distributed over the inner periphery of the said mold. *o*² is an adjustable stop for stopping the trolley *o* when the pourer *l* has reached the correct position for pouring 75 the metal in the mold.

75 The pourer may in some cases be divided in two sections in such a way that on rotating it, two different classes or kinds of metal may be introduced into the mold in two layers; for example in the case of casting a steel wheel-tire the first rotation of the pourer may introduce manganese steel for forming the tread of the tire, and the further rotation may introduce a softer-steel 80 to complete the inner portion of the casting.

85 Such a mold is shown in Figs. 4 to 7 and as will be seen the pourer *l* is divided by the internal partition *l*² which extends longitudinally down its center from one end 90

95 to the other. The mold *b* is provided with a central longitudinal passage 100

105 which is closed at the top by a cover 110

5 nearly to the other so as to form the two compartments l^3 and l^4 which are separated at the latter end by the radial partition l^5 . Each compartment is furnished with a pouring opening q the two openings being out of alinement with one another so that when the pourer is tilted the metal, say manganese steel, say from the compartment l^3 is first introduced into the mold and is followed 10 by the metal from the compartment l^4 .

Claims:

- 15 1. A pouring mechanism comprising a support, a member swiveled to said support for horizontal oscillation, bearings fixed to said member, a rock shaft carried by the bearings and having an operating handle, and a pourer fixed to said shaft.
2. The combination with a centrifugal

20 mold, of a carriage movable toward and away from the mold, a member swiveled to said support for horizontal oscillation, bearings fixed to said member, a rock shaft journaled in the bearings and having an operating handle, and a pourer fixed to said rock shaft and adapted to enter said mold. 25

3. A pourer for a centrifugal casting machine divided into two sections or compartments by a partition, each of said compartments having a pouring opening which is displaced relatively to the other, whereby 30 when the pourer is tilted the metal is discharged from the two compartments successively, substantially as hereinbefore described.

FRANCIS WILLIAM STOKES.
